UNITED STATES PATENT OFFICE.

ALDEN B. STARR, OF NEW YORK, N. Y., ASSIGNOR TO STARR PACKAGE MACHINERY COMPANY, INC., A CORPORATION OF MASSACHUSETTS.

TUBE-MAKING MACHINE.

1,077,764.

Specification of Letters Patent.

Patented Nov. 4, 1913.

Application filed January 27, 1913. Serial No. 744,290.

To all whom it may concern:

Be it known that I, ALDEN B. STARR, a citizen of the United States, residing at the city of New York, in the borough of Manhattan and State of New York, have invented certain new and useful Improvements in Tube-Making Machines, of which the following is a full, clear, and exact description.

10 This invention relates to improvements in machines for manufacturing continuous spirally-wound tubing of paper or other analogous material and has special reference to that class of machines in which the material is laid spirally around a mandrel and moved continuously along the same by a presser-belt or belts which lead around the material and the mandrel and which are driven in the direction and at the angle 15 necessary to wind the strips into a tube in which they are joined by abutting or overlapping edges and with the layers so applied as to break joints.

The object of the invention is to provide 25 improved means for transmitting power from the main driving shaft of the machine to the presser belts. In the operation of such machines, it is required to increase or decrease the space between the pulleys over 30 which the presser-belts run in order to compensate for various sizes of tubes to be made, and it is likewise necessary to change the angle at which the presser belts co-operate with the mandrel. To accomplish 35 these things, it is evidently necessary to provide a driving mechanism which will effectively drive the pulleys in whatever position of adjustment they may occupy. The driving mechanism herein described and comprising 40 my invention accomplishes this in a simple and entirely practical manner.

The invention will now be described in detail with reference to the accompanying drawings, in which,

45 Figure 1 is a plan of the machine showing the pulleys and presser-belts in two different angular positions, one of which is portrayed in dotted lines; Fig. 2 is a side elevation of the machine with the parts 50 shifted so that the presser-belts will occupy a substantially right-angular position with respect to the mandrel; and Fig. 3 is an elevation of the driving end of the machine when the parts are arranged as shown in 55 Fig. 2.

The main frame or table upon which the mechanism is mounted is indicated by 1 and comprises, in general, an elongated rectangular bed supported upon legs. Rising from one end of this bed is a bracket 2 in which is to be secured a mandrel 3 in such a manner that it is held against rotation, as by means of set-screws 4. The mandrel is arranged at considerable elevation above the table 1 and extends longitudinally and approximately along the center line thereof. Mounted crosswise upon the top surface of the table 1 are two swinging plates or frames 5 and 6, each of which is pivoted to the table top in order to swing in a horizontal plane, by means of a stud-bolt 7 (Fig. 3), the pivot being arranged substantially at the middle point of each plate and the plates extending some distance beyond the opposite edges of the table. The two plates 70 are connected together by a bar 8 which is pivotally attached to each by means of a pivot-screw shown in Fig. 3, and the purpose of which is to insure that when one of the plates 5 or 6 is swung upon its pivotal center, the other will follow it and the plates will always maintain a parallel relation to each other. The plate 5 is provided at each end with a vertically-rising bracket 9 and 75 10, respectively, which carries two bearings 80 11 and 12 for vertical shafts 13 and 14. Between the members of each pair of these bearings is a pulley 15 and 16 respectively, around which the presser-belts are led, as hereinafter described. The shaft 13 is connected with the shaft 14 by means of a horizontal shaft 16, which has its bearings respectively in the brackets 9 and 10, the connections being formed by means of beveled gears 17 and 18 as to the shaft 13, and 19 85 and 20 as to the shaft 14. The gear 20 is splined to the shaft 16 so that it may slide along the same and still receive in all positions the rotary motion of the shaft. Shaft 13 extends downward through the end of 90 plate 5 and some distance therebelow where it is further supported by a bearing in bracket 21 and carries at its lower end a driving sprocket-wheel 22. The bearing bracket 9 is fixed to the end of plate 5 while the bearing bracket 10 is mounted to be adjustable longitudinally upon said plate, the adjustability being provided by the slide 23 which moves in a groove or slot 24 of the plate. The adjustment of the bracket 105 110

along this plate is accomplished by means of a hand-wheel 25 carrying a screw 26 which works in a nut attached to the plate 23. This being a common construction the 5 nut and other details of the slide are not fully illustrated. When once adjusted the bracket is fixed by means of the bolt 27. It will be seen from this construction that when the sprocket wheel 22 is driven, the 10 pulleys 15 and 16 will both be positively driven regardless of the distance between them. The plate 6 is equipped with exactly the same mechanism as that which has been described above in connection with the plate 15 5. That is to say, it carries two pulleys the shaft of one of which is provided with a driving sprocket-wheel which we will identify by 22' while the other pulley is mounted to be adjustable along the length of the 20 plate.

As a means for swinging the plates 5 and 6 upon their pivots 7, I provide the hand-wheel 28 and screw 29. The screw is mounted to swivel at 30 in a bracket 31 fixed 25 at the side of the table and it works in a nut 32 which is also swiveled to the under-side of the end of plate 5. The screw is held from longitudinal movement in the swivel 30 so that when the hand-wheel 28 is rotated, the plate 5 together with the plate 6 is swung toward or away from the dotted position shown in Fig. 1.

The main driving shaft of the machine is indicated by 33, and power is communicated to it by means of a cone-clutch 34 which is caused to engage the driving pulley 35 by means of the usual forked shifting lever 36 provided with a handle 37 which works over a retaining notched quadrant of any usual construction. The shaft 33 leads along the under side of the table 1 to a point about midway between the two plates 5 and 6, where it is provided with a beveled pinion 34' which engages with a 40 horizontal beveled gear 35' running upon the lower end of a stud-shaft 36' depending from the table. Attached to the gear 35' is a sprocket-wheel 37' located in the same horizontal plane with the sprocket-wheels 22 and 22', its position with respect thereto being such that the three sprocket-wheels are at the angles of a triangle. The sprocket-wheels are connected together by a 45 endless drive-chain 38 which passes around each of them, so that the vertical shafts 13 and 14 of both plates 5 and 6 and the pulleys thereon are driven through the intermediacy of the chain.

In order to take up slack in the chain, 50 due either to the stretching thereof or to any changes in the length of the periphery of the triangular run of the chain when the plates are adjusted to different positions, I provide an ordinary form of belt-tightener 55 consisting of a sprocket-wheel 39 mounted

in a slide 40 on the under side of the table, the slide being moved by a screw 41 which is turned by a hand-wheel 42. By this adjustment the sprocket-wheel 39 can be moved toward or away from the chain in 70 whatever position it may be to take up the slack therein. In case a belt is used in place of the chain, the sprocket-wheels will all be substituted by smooth pulleys, which is an obvious modification and it is to be understood that the word "belt" used in the appended claims is intended to cover either a chain or belt of any character. 75

The presser-belts for laying the paper strips upon the mandrel are shown only in dotted lines in Figs. 1 and 3 since these devices form no part of my invention. One belt is applied to the pulleys on each of the plates 5 and 6. The belts are endless and one of the runs thereof makes a complete 80 turn or wrapping around the mandrel while lying flat thereagainst. This is indicated in Fig. 3 where the dotted lines 43 indicate the belt.

In the operation of making a tube, a strip 90 of paper is applied to the mandrel at substantially the same angle as the plate 5 occupies, the end of the strip being inserted between the wrapping of the belt and the surface of the mandrel, so that the movement of the belt will draw the strip inward and warp it around the stationary mandrel. The spiral winding is thus fed along upon the mandrel to the belt carried by the plate 6, which moves it along and simultaneously 95 applies another strip of paper thereover. The first strip is usually free from adhesive material, but the second and succeeding strips are coated with an adhesive upon the surface which is applied to the layer already in place, and the second and succeeding layers are usually introduced so as to 100 break joints with those next to them. 105

The machine ordinarily runs continuously, but may of course be stopped and started at 110 will whenever necessary. Different sizes of mandrels are used in order to make tubes of different diameters so that when a change in diameter is made, the presser-belts must be either slackened or tightened by adjusting the 115 distance between pulleys 15 and 16. The angle at which the strips of paper are to be spirally laid on is often to be changed, depending upon the kind of tube to be made, and to accomplish this the plates 5 and 6 120 carrying the presser-belts must be swung upon their pivots 7 in the manner before described. This motion, however, is readily accomplished in my machine without disconnecting the power or interfering with the 125 drive from shaft 33 to the pulleys, since the connection remains intact in all positions to which the belts may be adjusted. The sprocket wheel or pulley 37' may be understood as the main power pulley of the ma- 130

chine, since power may obviously be delivered to it in a variety of ways. This pulley is necessarily eccentric to the centers of at least one of the plates 5 and 6 but may be 5 concentric with one of said centers. Since it is possible to make tubes by using only one of the plates 5—6 and the mechanism which it carries, the second plate herein shown may be regarded merely as a swinging lever 10 whose function is to carry the sprocket wheel or pulley 22'.

Having thus described my invention, what I claim is:

1. In a tube forming machine, the combination of two plates mounted to swing on different centers and carrying presser-belts and driving pulleys, a fixed power driven pulley arranged eccentrically and in the same plane with said pulleys, and an endless belt 15 communicating power from said pulley to the pulleys carried by said plates, substantially as described.
2. In a tube forming machine, the combination of a pair of presser-belt carrying plates mounted to swing on different centers, a driving pulley carried by each plate, a fixed power driven pulley eccentric and in the same plane with the pulleys carried by 25 the plates, and an endless belt leading around all three pulleys, substantially as described.
3. In a tube forming machine, the combination of a pair of presser-belt carrying plates mounted to swing on different centers, a driving pulley carried by each plate, a fixed power driven pulley mounted eccentrically to the center of at least one of 30
- 35

said plates and in the same plane with said pulleys and an endless belt leading around all three pulleys, substantially as described.

4. In a tube forming machine, the combination of a pair of presser-belt carrying plates mounted to swing on different centers, a pulley carried by each plate, a fixed power driven pulley eccentric to but in the same plane with the driving pulleys carried by the plates, an endless belt leading around all three pulleys and a belt tightener co-operating with said belt, substantially as described. 40 45

5. In a tube forming machine, the combination of a plurality of plates mounted to swing on different centers and one at least carrying a presser-belt and pulleys therefor, a driving pulley carried by each plate, a fixed power driven pulley eccentric to but in the same plane with the pulleys carried by the plates, and an endless belt leading around 50 55 all three pulleys, substantially as described.

6. In a tube forming machine, the combination of a plurality of presser-belt carrying plates mounted to swing on different centers, a driving pulley carried by each plate, a fixed power driven pulley eccentric to but in the same plane with the pulleys carried by the plates, and an endless belt leading around all of said pulleys, substantially as 60 65 described.

In witness whereof, I subscribe my signature, in the presence of two witnesses.

ALDEN B. STARR.
